3 Sheets-Sheet 3

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed December 12, 1923. Serial No. 680,153.

This invention relates to posting and billing by the use of a typewriting and computing machine, and more particularly to the typing of entries concurrently upon superposed work-sheets, such as statement, ledger and proof sheets, and for other purposes. The ledger and statement sheets pertaining to a customer's account have been usually coupled together throughout the month, and inserted together with an interleaved carbon over the record-sheet in the machine from time to time for entering transactions thereon (as in Kidder Patent No. 1,223,075, dated April 17, 1917). At the end of the month the statement-sheet was sent to the customer, while the ledger-sheet was placed with the succeeding month's statement-sheet of the same customer to receive further entries. In accordance with this system, it was necessary to interleave a carbon-sheet with the ledger and statement sheets preparatory to the typing of each entry, and to strip this carbon from between the sheets after an entry had been made. One of the sheets, of necessity, received carbon impressions, which was not wholly satisfactory, since the statement had to be mailed to the customer, and the ledger-sheet had to be preserved for a permanent record.

It is an object of the present invention to overcome these objections while preserving the advantages of making entries upon the statement and ledger sheets at a single operation. To this end, provision is made in a typewriting machine of a main ribbon and of a duplicating or auxiliary ribbon, the auxiliary ribbon being arranged to lie between the statement and ledger sheets to print upon the underneath one of said sheets, say the ledger-sheet. With this arrangement the operator is required only to place the statement and ledger sheets in the machine, guiding them to opposite sides of the auxiliary ribbon, to collate them with relation to each other and to the proof-sheet, to type an entry, and to replace them in their receptacle near the machine to await a further entry. There is no need to interleave a carbon-sheet between the statement and ledger sheets, and both of these sheets receive ribbon-impressions.

In accordance with one feature of the invention, provision is made of means for moving the auxiliary ribbon to a work-inserting and collating position such that the statement and ledger sheets may be quickly and easily positioned at opposite sides of the ribbon and then collated without danger of catching upon the ribbon and fouling it. To this end, the auxiliary ribbon may be carried by an auxiliary ribbon-frame pivotally mounted on the platen-frame and swingable to carry the auxiliary ribbon upwardly and rearwardly away from the platen and approximately parallel with the face of a collating table. The auxiliary ribbon-frame-lifting means is arranged to be operated by a ribbon-frame-lifting lever pivoted on the carriage of the machine. The ribbon-frame-lifting lever may be located in proximity to the line-space lever and may be coaxial with said lever, the arrangement being such that either of said levers may be operated independently of the other, or both of them may be operated at a single stroke, if desired. This arrangement is particularly advantageous because of the fact that a statement and ledger entry usually, but not always, consists of a single typed line.

An important feature of the invention resides in the combination with the main and auxiliary ribbon mechanism of means for controlling a proof-sheet during the insertion and collation of the statement and ledger sheets and for assisting such insertion and collation. Provision is made of a rear insertion chute for guiding the ledger and statement sheets to the desired field of the platen and of a support for the rear end of the proof-sheet to hold it away from the rear insertion chute so as not to interfere with the rear insertion of the ledger and statement sheets into the machine. A collating frame has a roller to run upon the platen at the upper front portion thereof to hold the proof-sheet thereagainst, and has guides for engaging the side edges of the proof-sheet at the delivery side of the platen to prevent lateral shifting or skewing of the sheet when the main feed-rolls are cast off from the platen. A collating table on the collating frame at the delivery side of the platen includes side gages for the ledger-sheet and a clamp for detaining it in adjusted position while the statement-sheet is

- being collated over it, and while the auxiliary ribbon is being returned downwardly from its sheet-collating position to its printing position.
- 5 When it is desired to insert ledger and statement sheets into the machine, the auxiliary ribbon-frame is swung to lift the auxiliary ribbon to work-inserting position and the feed-rolls are cast off from the platen.
- 10 The ledger and statement sheets are inserted around the platen from the rear with the leading edge of the duplicate sheet, which may be the ledger-sheet, substantially in advance of the leading edge of the original sheet, which may be the statement-sheet. The operator presses the upper margin of the duplicate sheet back with the fingers of one hand to guide it to the rear of the auxiliary ribbon while advancing both sheets with the other hand, and then releases the pressure while continuing the advance of the sheets to cause the original sheet to be advanced in front of the auxiliary ribbon. The work-inserting position of the auxiliary ribbon is especially designed to facilitate this operation, the ribbon in this position being located a substantial distance out from the platen, and yet a considerable distance behind the path naturally followed by a work-sheet fed forward freely from the platen.
- 20 He next adjusts the duplicate (ledger) sheet to the correct writing position and clamps it by the clamp on the collating table, after which he adjusts the original (statement) sheet to writing position, makes the main feed-rolls effective, and casts off the clamp. He then presses a finger-piece for lowering the auxiliary ribbon-frame to locate the auxiliary ribbon in writing position and types the entry.
- 25 The auxiliary ribbon, lying as it does between the statement and ledger sheets, will not only print upon the face of the ledger-sheet which is desired, but will also print upon the back of the statement-sheet which is objectionable unless this result is guarded against. In accordance with one feature of the invention, provision is made to prevent the typing of impressions upon the back of the statement-sheet. This may be done by mounting a shield to lie between the auxiliary ribbon and the back of the statement-sheet, which shield may consist of a strip of paper of about the same width as the auxiliary ribbon held in place over the auxiliary ribbon by spring clamps mounted on the opposite ends of the auxiliary ribbon-frame. These clamps are preferably so constructed that they tend to tension the shield strip as they are moved to clamping position. The shield strip is, therefore, held before the auxiliary ribbon under tension, and thus helps to overcome the tendency of the statement sheet to displace the auxiliary ribbon at line-feeding. The shield or the

like prevents the outside work-sheet from becoming smudged from repeated insertions and withdrawals of the unit during the month in which the account is accumulating.

An Underwood "bookkeeping" or combined adding and typewriting machine, embodying the present improvements, forms a unit which renders it practicable in a revolute platen machine to carry out the method of accounting above given, viz., making entries and computations item by item from day to day upon an original bill and its companion original ledger-sheet, coupled together throughout the month, to be separated at the end of the month, when the bill is sent to the customer and the ledger-sheet (if filled) is permanently bound.

Other features and advantages will hereinafter appear.

In the accompanying drawings, Figure 1 is a front elevation of a part of an Underwood combined adding and typewriting machine embodying the present improvements.

Figure 2 is a fragmentary sectional side elevation, showing the platen-frame and auxiliary ribbon mechanism of the machine.

Figure 3 is a sectional side elevation of substantially the same part of the machine shown in Figure 1.

Figure 4 is a fragmentary top plan view, showing particularly the construction of the ribbon-raising mechanism.

Figure 5 is a diagrammatic side elevation, showing the auxiliary ribbon raised to work-inserting position.

Figure 6 is a detail view of one of the side members of the rear insertion chute.

Figure 7 is a view similar to Figure 1, but on a larger scale, and showing the ribbon mechanism in greater detail.

Figure 8 is a sectional side elevation taken through the right end of the platen-axle.

Figure 9 is an enlarged detail view, showing particularly the construction of the ribbon-shield holder.

Figure 10 is a horizontal sectional view, showing the details of construction of the ribbon-shield holder, the holding clamp being shown in effective position.

Figure 11 is a view similar to Figure 10, but showing the holding clamp in ineffective position.

The Underwood combined typewriting and computing machine with which the present improvements are combined includes computing mechanism which comprises denomination-selectors 5, denominational jacks 6 co-operating therewith, and zone-selectors 7, and tabulating mechanism which comprises tabulating stops 8 and co-operating decimal-stops 9 for locating the traveling carriage quickly in the desired columns of the computing zones. For a more complete disclosure of the computing and tabulating

mechanism, reference may be had to the patent to Gumprecht, No. 1,237,895, granted August 21, 1917.

Types 10 are swung upward and rearward 5 by the operation of keys (not shown) between the jaws of a type-guide 11 to strike through the usual vibratory ribbon 12 against the front of a cylindrical platen 13, journaled by its axle 14 in the ends 15 of a 10 platen-frame 16, which frame is vertically shiftable between upper and lower case positions in a traveling carriage 17. A line-space lever 18, mounted to swing about a vertical fulcrum 19 on the carriage 17, may be 15 operated by its handle 20 to thrust to the rear a line-space slide 21 carrying a pawl 22 to engage and rotate a line-space ratchet-wheel 23 that has driving connection with the platen-axle 14. Feed-rolls 24 co-operate 20 with the platen 13 to feed the work at line spacing, and these feed-rolls may be cast off, when desired, by the usual finger-piece (not shown).

An auxiliary ribbon 25, to lie behind the 25 statement-sheet A and print upon the ledger-sheet B, is carried by an auxiliary ribbon-frame 26, comprising a rock-shaft 27 journaled in the ends 15 of the platen-frame 16, and end plates 28 fast on the rock-shaft 27. 30 Each of the end plates 28 supports a ribbon-spool 29 for rotation about a transverse horizontal axis. The end plates 28 extend forwardly to positions slightly in advance of the front of the platen 13 to form ribbon-guides. Their forward ends are bent substantially at right angles to direct them toward each other, whereby ribbon-guiding portions 30 are provided extending transversely of the machine (see Figure 9). The 35 portions 30 extend inwardly to points slightly beyond the inner flanges of the ribbon-spoils 29, where they are bent forwardly to provide ribbon-guiding portions 31 which terminate at their upper ends in arms 32. 40 Rolls 33, having ribbon-guiding flanges 34 upon them, are mounted in aligned openings 35 in the arms 32 and in the main bodies of the plates 28. Inclined slots 36 in the 45 portions 30 and vertical slots 37 in the portions 31 guide the auxiliary ribbon 25 down from the spools 29 and direct it across the 50 face of the platen 13.

In order to prevent the auxiliary ribbon 25 from making type impressions on the back 55 of the statement-sheet A, and from smudging the sheet during the necessary numerous insertions and withdrawals of the same sheet, provision is made of a shield 38. This shield 38 consists of a strip of paper of about the 60 same width as the auxiliary ribbon 25, which is held in position to cover the auxiliary ribbon by clamps 40 mounted at the opposite ends of the auxiliary ribbon-frame 26. One 65 of these clamps 40 comprises a resilient U-shaped member having one leg 41 secured to

an end plate 28 of the auxiliary ribbon-frame and a second leg 42 forming a stationary clamp-jaw. Horizontal ears 43, turned outward from the upper and lower extremities of the leg 42, support a pivot-pin 44 of a movable resilient clamp-jaw 45. The movable jaw 45 has a finger-piece 46 whereby it may be swung to and from clamping position. The arrangement of the jaws 42 and 45 is such that the movement of the 70 swinging jaw 45 to clamping position tends to tension the shield strip 38, thus assuring that the shield strip will be held before the auxiliary ribbon 25 under tension and will help to prevent displacement of the ribbon 80 25 in the direction of paper-feeding.

The auxiliary ribbon 25 is fed endwise by mechanism not shown herein, but the feeding mechanism may be like that disclosed in the application of Kurowski, Serial No. 55 589,064, filed September 19, 1922 (now Patent No. 1,564,861, dated December 8, 1925).

The auxiliary ribbon-frame 26 is normally urged by spring pressure into position to hold the auxiliary ribbon 25 in writing position. Since it would be difficult, however, to insert a work-sheet between the auxiliary ribbon 25 and the platen 13 with the auxiliary ribbon in writing position, and since frequent insertion of sheets is necessary due 95 to the fact that a ledger and statement entry generally consists of a single line only, provision is made of means for moving the auxiliary ribbon 25 up to a work-inserting position where the insertion of the sheets at 100 opposite sides of the ribbon may be quickly and easily effected. In work-inserting position, the auxiliary ribbon 25 is located somewhat to the rear of the path naturally followed by a work-sheet fed forward freely 105 from the platen 13, but is spaced out a considerable distance from the platen. By inserting the sheets with the inside one in advance of the outside one and pressing the leading margin of the inside sheet to the 110 rear, the sheets can be readily caused to pass up from the platen 13 at the opposite sides of the auxiliary ribbon 25, as shown in Figure 5.

The mechanism for swinging the auxiliary 115 ribbon-frame 26 to move the auxiliary ribbon 25 to work-inserting position includes a projection 47 on the left end plate of the auxiliary ribbon-frame and a cam 48 engaging the projection 47 and movable to lift it. 120 The cam 48 is carried by a ribbon-frame-lifting slide 49, which is slidingly mounted on the top or lateral extension of the left end 15 of the platen-frame 16 by means of headed screws 50 (Figure 4) that pass 125 through slots 51 in the slide 49 and are threaded into the end member 15 of the platen-frame. An auxiliary ribbon-frame-lifting lever 52 is pivoted on the carriage 17 of the machine above the line-space lever 18 130

for rotation about the same fulcrum 19 as the line-space lever, and this ribbon-frame-lifting lever 52 has a toe 53 which is received in a vertically-extending slot 54 in the forward end of the ribbon-frame-lifting slide 49 for actuating the slide. The slot 54 is of sufficient extent to permit case-shifting of the platen-frame 16 relatively to the lever 52. The slide 49 is moved to the rear by actuation of the lever 52, and is moved forward as soon as the lever 52 is released, by a return spring 55 connected to the slide 49 and to the platen-frame. The auxiliary ribbon-frame 26, however, is latched in its raised position by means which will be described later.

As has been stated, an entry on the statement and ledger sheets generally consists of a single line only. In some cases, however, it may consist of two or more lines. It is an important feature of the invention that the auxiliary ribbon-raising lever is mounted with its handle 56 near the handle 20 of the line-space lever, and is arranged so that the two levers 18 and 52 can be operated by a single stroke of the hand, if desired. Such operation would naturally be desired in every case where the entry consists of a single line; whereas independent actuation of the line-space lever 20 would be desired at the conclusion of every line but the last of an entry consisting of two or more lines.

The auxiliary ribbon-frame 26 is detained in work-inserting and collating position when raised thereto, as at Figure 5. A cam 57, fixed upon the rock-shaft 27 of the auxiliary ribbon-frame 26, has a shoulder 58 (Figure 8) in front of which a finger 59 on a pivoted latch 60 is snapped by a spring 61 (Figure 3) to prevent lowering of the auxiliary ribbon-frame 26 until such time as the latch 60 is actuated by its finger-piece 62 to release the frame 26. The latch 60 holds the auxiliary ribbon 25 in sheet-collating position, a trifle away from the platen, and a little above the printing position of the ribbon, thus affording clearance for the collation of sheets at both back and front of the auxiliary ribbon, the latter being below the table 77 on which the sheets are being collated.

Provision is also made of means for facilitating the insertion of the statement and ledger sheets at the back of the platen 13 and for assisting in the collation of said sheets with relation to each other and to a proof-sheet C. A rear guide-chute 63 for the statement and ledger sheets, consisting of an extension 64 of the rear paper-shelf 65 and side walls 66 adjustable along the extension 64 for different widths of work-sheets, is connected to the rear paper-shelf 65 by a rod 67 and to the ends 15 of the platen-frame by brackets 68. A proof-sheet support 69 is connected by rearwardly-extending arms 70 to the extension 64 and sup-

ports the rear end of the proof-sheet C out of the way of the rear insertion guide-chute 63, so that the statement and ledger sheets may be inserted without obstruction.

A collating frame 71 is provided for holding the proof-sheet C, with a superposed carbon-sheet C', stationary during the insertion and adjustment of the statement and ledger sheets, and for facilitating the adjustment of the latter sheets. The collating frame 71 comprises end brackets 72 pivotally mounted on the rock-shaft 27 and a plate 73 connecting the brackets 72. The end brackets 72 support a roll 74 at their lower front extremities, which is normally swung into clamping engagement with the platen 13 to hold the proof-sheet C, with the superposed carbon-sheet, stationary during the insertion and collation of the statement and ledger sheets.

Rearwardly-extending fingers 75, adjustably mounted on a transverse rod 76 carried by the end brackets 72, serve as side guides for the proof-sheet C, and materially assist the roll 74 in maintaining the proof-sheet against slipping or skewing, when the main feed-rolls 24 are cast off. A front collating table 77, consisting of complementary right and left members 78 having side walls 79 in alignment with the side walls 66 of the rear insertion chute 63, is mounted on the connecting plate 73 of the collating frame 71.

The ledger and statement sheets, as has been previously stated, are introduced in the machine with the leading edge of the inside ledger-sheet B a substantial distance in advance of the leading edge of the outside statement-sheet A, for the purpose of facilitating the placing of these sheets at opposite sides of the auxiliary ribbon 25. When the sheets have been thus introduced and placed in the machine, the inside ledger-sheet B (which is considerably wider than the outside statement-sheet) is first adjusted to writing position, reference being had to a protruding right-hand margin of the ledger-sheet B to determine the correct writing line. The ledger-sheet B is then clamped to the face of the collating table 77 by a clamp 80 mounted at one side of the collating table to engage the protruding margin of the ledger-sheet. The clamp 80, which thus holds the ledger-sheet B stationary during adjustment of the statement-sheet A, may consist of a swinging jaw 81, pivoted in a bracket 82 on the right section 78 of the collating table 77, and a handle 83 for swinging the jaw 81 between effective and ineffective positions. A double-acting tension-spring 84 is arranged to hold the clamp-jaw 81 in either effective or ineffective position.

During the adjustment of the statement-sheet A there is a tendency for the rear end of the ledger-sheet B to be lifted accidentally from the rear insertion chute 63 and

to become skewed. To overcome this, a finger 85 is provided on the left side guide 66 of the rear insertion chute for holding the ledger-sheet B down in the chute.

5 At each insertion of the coupled bill and ledger sheets in the machine, an item is entered thereon and a computation is simultaneously performed, as, for instance, the one that is explained in the application of Vick-
10 ers, No. 661,540, filed September 8, 1923 (now Patent No. 1,600,023, dated September 14, 1926).

The collating table overlies one portion only of the platen, and is substantially narrower than the proof-sheet, the laterally-projecting portion of which is exposed by the auxiliary ribbon when the latter is in its raised position, thus permitting typing through the main ribbon directly upon the 20 proof-sheet.

When a fresh proof-sheet C is to be inserted in the machine or when an erasure on the proof-sheet is necessary, it is desirable to swing the collating frame 71 and the auxiliary ribbon 25 up out of the way. The collating frame 71 is swingable about the rock-shaft 27, and has a notch 86 at its rear arranged to be engaged by a spring-pressed detent 87 to hold the collating frame in an 30 elevated position. A projection 88 on the collating frame 71 is arranged to engage a projection 89 on the auxiliary ribbon-frame 26 to cause it to be swung up with the collating frame. Since the collating frame 71 and the auxiliary ribbon-frame 26 are coaxially mounted, these frames swing up as if they were a unitary structure without any tendency to interfere with each other. On the 35 return of the collating frame 71 to normal position, the auxiliary ribbon-frame 26 will be arrested by the latch 60 and detained in work-inserting position ready for the insertion of statement and ledger sheets. It will be observed that the auxiliary ribbon 25 is 40 withdrawn from between the ledger and statement sheets when the collating frame 71 is swung upward for making erasures. Since this leaves the ledger and statement sheets without any interposed copying medium, there is no tendency for the erasing 45 on the statement-sheet A to smear the ledger-sheet B, and hence the usual steps to guard against this smearing are unnecessary.

The statement and ledger sheets may be 50 kept together in a holder, on the bookkeeping-machine-supporting stand, of the kind disclosed in the patent to Kidder, No. 1,278,678, granted September 10, 1918. When an entry is to be made, the sheets are 55 removed from the holder and inserted in the machine without the necessity of inserting a carbon, and when the entry has been completed, the statement and ledger sheets are 60 returned to the holder to await further entries.

When the statement and ledger sheets have been positioned for writing, the operator first copies the old balance, and runs it into the computing mechanism. He then writes the debit or credit entry, runs this 70 also into the computing mechanism, and then copies the new balance from the total exhibited by the computing mechanism. It will be seen that the items appearing on both of the ribbon-copies are both typed and 75 completed simultaneously so that comparison to assure correspondence is unnecessary.

It will be understood that the organization including the auxiliary ribbon supported on the carriage, with the collating table, eliminates the necessity of the carbon-sheet that has been necessary heretofore between the collated sheets. The carbon-sheet has been highly objectionable, as it required considerable care and time to manipulate. The carbon-sheet was also liable to smudge the ledger-sheet and to become dislocated while adjusting the statement-sheet relatively to the previously adjusted ledger-sheet. By the use of an auxiliary ribbon with the collating device all this care is eliminated, and consequently the operation of inserting the sheets to be collated is expedited.

Heretofore it has been the practice in some instances to have the right-hand edge of the ledger-sheet (nearest the platen) extend slightly beyond the right-hand edge of the statement-sheet to enable a mark to be made on the ledger-sheet opposite each last entry of a series, said mark indicating the last entry on the record-sheet and serving to assist in adjusting the statement-sheet relatively thereto at a subsequent insertion of the statement-sheet and ledger-sheet into the machine. With the present arrangement of the collating device and auxiliary ribbon, the marks may be omitted, since the statement-sheet may be readily moved temporarily to one side of the platen to expose the underlying ledger-sheet sufficiently to observe the last entry, so that the ledger-sheet may be adjusted to the writing line. After the ledger-sheet has been adjusted, the statement-sheet may be moved back into overlapping relationship and may be adjusted 105 to the writing line.

The statement-sheet and ledger-sheet may also be inserted around the platen in the following manner: The statement or outer sheet may be first inserted around the platen from the back, and brought forwardly in front of the auxiliary ribbon, said ribbon having previously been lifted to its sheet-inserting and collating position. Since the leading edge of any work-sheet has a tendency to move away from the platen, it will be understood that the leading edge of the statement-sheet, as it is advanced upwardly in front of the platen, naturally advances in front of the displaced auxiliary ribbon with- 120 125 130

out interference therewith. After the statement-sheet has been thus inserted, the ledger-sheet may be inserted from the front of the machine by introducing its lower edge between the platen and the auxiliary ribbon, which auxiliary ribbon, in its sheet-inserting position, stands a considerable distance away from the platen to allow the ledger-sheet to be freely inserted between it and the platen. The ledger-sheet may then be pushed down around the platen behind the statement-sheet and adjusted to the desired position.

Variations may be resorted to within the scope of the invention, and portions of the improvements may be used without others.

Having thus described my invention, I claim:

1. A typewriting machine for typing items to be billed and posted, having a revoluble platen, a statement and ledger sheet collating device, including a collating table disposed above the platen at the delivery side thereof, a mechanism for presenting a ribbon to the outer of two work-sheets, and mechanism for feeding an auxiliary ribbon between the outer work-sheet and the inner work-sheet to make a permanent record copy upon the inner work-sheet, said auxiliary ribbon-mechanism including a back-print-prevention shield for the auxiliary ribbon, and devices for shifting said auxiliary ribbon and said shield to a sheet-collating position adjacent the lower end of said collating table, so that said auxiliary ribbon and said shield will be disposed in the rear of said main ribbon and substantially parallel to the work-face of said collating table to avoid smudging the outer work-sheet during numerous insertions and removals of the same.

2. In a typewriting machine having a revoluble platen, around which may be fed together an outer statement-sheet and an inner ledger-sheet, and a collating table having its lower end positioned a short distance above the printing line of said platen, the combination with a main vibrating ribbon for typing on said statement-sheet, and an auxiliary ribbon laterally fed along the printing line of said platen, adjacent the rear side of said main ribbon, for typing on said ledger-sheet, of means for inserting and collating said statement and ledger sheets in said machine, to avoid smudging said statement-sheet during the numerous insertions and withdrawals of the same, said means including a detachable back-print-prevention shield for said auxiliary ribbon, mechanism for raising said auxiliary ribbon and said shield upwardly and rearwardly to an inserting and collating position wherein they are disposed adjacent the lower end of said collating table and substantially parallel to the face of the latter, and automatic de-

vices for latching said mechanism to hold said auxiliary ribbon and said shield in their raised positions, said devices being manually releasable, whereby said auxiliary ribbon and said shield may be lowered to typing positions when said statement and ledger sheets are collated.

3. In a typewriting machine having a main vibrating ribbon, and an auxiliary ribbon normally disposed closely adjacent the rear surface of said main ribbon, the combination with a platen, of means for inserting and collating a statement, ledger and proof sheet in position for having items billed and posted in ink on the statement and ledger sheets, said means including a rear insertion guide-chute for the statement and ledger sheets, a support for holding the rear end of the proof-sheet clear of said rear insertion guide-chute, devices at the front of the platen co-operating with said support for holding the proof-sheet against accidental displacement while the statement-sheet and proof-sheet are being collated, a collating table disposed at the delivery side of said platen and having its lower end terminating a short distance above the printing line of the platen, mechanism for moving said auxiliary ribbon from typing position to sheet-collating position substantially parallel to the face of said collating table, and instrumentalities for latching said auxiliary ribbon in a sheet-collating position whereby increased space is provided for said statement-sheet to be fed upwardly behind said main ribbon and in front of said auxiliary ribbon and on said table, and for said ledger-sheet to be fed upwardly behind said auxiliary ribbon and on said table.

4. In a typewriting machine having a platen, in combination, a swingable frame arranged for normally carrying an auxiliary ribbon at the printing line of said platen, a swingable frame carrying a collating table above said platen, said ribbon-carrying frame being swingable upwardly to bring said ribbon in a statement-sheet and ledger-sheet-inserting and collating position adjacent the lower end of said collating table, means for swinging said ribbon-frame and said collating-table frame, as a unitary structure, from their normal positions upwardly and rearwardly to a position for inserting a tally-sheet around said platen, releasable devices for locking said frames in their tally-sheet-inserting positions, and instrumentalities effective for stopping said ribbon-carrying frame in its collating position upon release of said locking devices and the lowering of said frames.

5. In a typewriting machine having a platen, around which may be fed a plurality of work-sheets, and a main vibrating ribbon for typing on the outermost one of said sheets, the combination of mechanism for

- laterally feeding at the printing line an auxiliary ribbon between said outermost sheet and the next underlying sheet, a laterally-fixed back-print-prevention shield between said auxiliary ribbon and said outermost sheet, and instrumentalities releasably holding said shield, whereby the latter may be replaced when worn or soaked with ink without affecting said auxiliary ribbon.
- 10 6. In a typewriting machine having a platen, around which may be fed a plurality of superposed work-sheets, the bottom work-sheet having a marginal portion extending beyond the overlying work-sheets, and a main vibrating ribbon, the combination of displaceable mechanism for laterally feeding an auxiliary ribbon between the two outmost work-sheets, a back-print-prevention shield for said auxiliary ribbon, and instrumentalities on said mechanism releasably holding said shield, said mechanism being movable upwardly to raise said auxiliary ribbon and said shield from the printing line, to permit typing by said main ribbon on said marginal portion of said bottom work-sheet.
- 15 7. A combined typewriting and computing machine including a platen, a main ribbon, an auxiliary ribbon at the front and back of which work-sheets are positioned, a collating frame for clamping a proof-sheet with its superposed carbon against the platen to hold them against displacement while the other sheets are being adjusted, and for assisting in the adjustment of said sheets, the collating frame being swingable to a position to make the proof-sheet accessible for erasures, and means operable by the collating frame when so swung to withdraw the auxiliary ribbon a substantial distance from the platen, so that no copy medium will be interposed between the statement and ledger sheets where the erasure is to be made.
- 20 8. In a typewriting machine, in combination, a main ribbon for writing on an outside statement-sheet, an auxiliary ribbon for writing upon an inside ledger-sheet, line-spacing mechanism for advancing the work including a proof-sheet behind said first-mentioned sheets, said line-spacing mechanism including a line-space lever, and an auxiliary ribbon-controlling mechanism including a lever actuatable to move the auxiliary ribbon from writing position to a work-inserting position to facilitate the insertion of fresh statement and ledger sheets at opposite sides of the ribbon, the auxiliary ribbon-shifting lever being located in proximity to the line-space lever so that it may be engaged and actuated at the same operation with the line-space lever or independently thereof, the line-space lever being also operable independently of the auxiliary ribbon-shifting lever.
- 25 9. In a typewriting machine, in combination, a main ribbon for writing on an outside statement-sheet, an auxiliary ribbon for writing upon an inside ledger-sheet, line-spacing mechanism for advancing the work including a proof-sheet behind said first-mentioned sheets, said line-spacing mechanism including a line-space lever, and an auxiliary ribbon-controlling mechanism including a lever actuatable to move the auxiliary ribbon from writing position to a work-inserting position to facilitate the insertion of fresh statement and ledger sheets at opposite sides of the ribbon, the auxiliary ribbon-shifting lever being supported coaxial with the line-space lever, the line-space lever being arranged to be operated at the same operation with the auxiliary ribbon-shifting lever or independently thereof, as desired.
- 30 10. In a typewriting machine, the combination of a carriage, a platen on said carriage, an auxiliary ribbon on said carriage, means including a line-space slide to rotate the platen, means including a slide to control the auxiliary ribbon, means including two actuating fingers to swing about a common axis, one of said fingers engaging the line-space slide, the other finger engaging the ribbon-controlling slide, and platen-shifting mechanism, said slides being shiftable relatively to the actuating fingers during platen-shifting operations without disturbing the co-operative relation between said slides and said fingers.
- 35 11. In a typewriting machine, a ribbon for writing on an outside sheet, an auxiliary ribbon for writing on an inside sheet, and means for preventing the typing of impressions on the back of the outside sheet by the auxiliary ribbon, said means including a flexible back-print prevention shield through which type blows may be transmitted, and clamps for demountably holding the shield in front of the auxiliary ribbon under tension, each clamp consisting of a stationary jaw around which the shield is partially bent, and a swinging resilient jaw, the swinging jaw being arranged to be swung to clamping position in rubbing engagement with the shield in a direction to assure that the shield will be held before the auxiliary ribbon under tension.
- 40 12. In a typewriting machine, a ribbon for writing on an outside sheet, an auxiliary ribbon for writing on an inside sheet, a flexible shield extending between the auxiliary ribbon and the outside sheet, and clamps for holding the shield removably in place, each clamp comprising a stationary resilient jaw around which an end of the shield is turned, and a resilient swinging jaw swingable into position to resiliently clamp the turned end of the shield against the stationary jaw, the construction of the clamps being

such that the shield may yield towards the platen under the impact of the types due to the resiliency of the clamping jaws, the tension of the shield produced by the clamps preventing displacement of the shield and ribbon while feeding the sheets.

13. In a typewriting machine, a ribbon for writing upon an outside sheet, an auxiliary ribbon for writing upon an inside sheet, a flexible back-print prevention shield extending between the auxiliary ribbon and the outside sheet, and yielding means holding the ribbon shield under tension before the auxiliary ribbon to prevent displacement of the auxiliary ribbon by the feeding of the sheets and to prevent sagging forward of the auxiliary ribbon into the path of a work-sheet inserted at the front thereof, the arrangement being such that the shield although tense can yield towards the platen.

14. In a typewriting machine, a ribbon for writing on an outside sheet, an auxiliary ribbon for writing on an inside sheet, a flexible shield extending between the auxiliary ribbon and the outside sheet to prevent the typing of impressions on the back of the outside sheet, and clamps for holding the ends of the shield, each clamp comprising a stationary U-shaped resilient member having a supporting leg and a clamping leg resiliently connected to each other, and a jaw wedgeable into clamping relation with said clamping leg of the stationary member, the stationary U-shaped member yielding under the force of the type impact to prevent an undue tension on the shield, the wedgeable jaw being also resilient to maintain clamping contact with the relatively stationary jaw when the latter yields under the tension of the shield.

15. In a typewriting machine including a revolute platen, an insertion chute for a statement-sheet and a ledger sheet at the rear of the platen, a table for holding the rear end of a proof-sheet clear of the insertion chute, a collating table at the delivery side of the platen for locating the statement and ledger sheets with relation to each other and to the proof-sheet, means for holding the proof-sheet stationary during the insertion and collation of the statement and ledger sheets, comprising a roll at the delivery side of the platen to press the proof-sheet against the platen, and side gages at the delivery side of the platen for locating the proof-sheet endwise of the platen, said gages being close to said roll.

16. In a typewriting machine including a revolute platen, an insertion chute for the statement and ledger sheets at the rear of the platen, a support for holding the rear end of a proof-sheet clear of the insertion chute, a collating frame, comprising a collating table at the delivery side of the platen

for locating the statement and ledger sheets with reference to each other and to the proof-sheet, means for holding the proof-sheet against displacement during the insertion and collation of the statement and ledger sheets, comprising a roll on the collating frame to press the proof-sheet against the platen, and fingers extending downwardly and rearwardly from the collating frame into proximity to the platen to serve as side gages for the proof-sheet.

17. In a typewriting machine, in combination, a revolute platen, an insertion chute for a statement-sheet and a ledger-sheet at the rear of the platen, comprising side guides for the ledger-sheet, a front collating table having side guides for the ledger-sheet, a clamp co-operating with one of the side guides of the front collating table and the rear insertion chute to hold the ledger-sheet stationary in writing position during adjustment of the statement-sheet, and means on the rear insertion chute to prevent the accidental lifting of the ledger-sheet from between the side guides of the chute during adjustment of the statement-sheet.

18. In a typewriting machine, the combination of a carriage, a platen on said carriage, an auxiliary ribbon on said carriage, means including a line-space slide to rotate the platen, means including a slide to control the auxiliary ribbon, and means including two actuating fingers to swing about a common axis, one of said fingers engaging the line-space slide, and the other finger engaging the ribbon-controlling slide.

19. In a typewriting machine, the combination of a carriage, a platen, a platen-frame on said carriage having a laterally-extending lip at its top edge, an auxiliary ribbon on said carriage, means including a line-space slide under said lip to rotate the platen, means including a slide above said lip to control the auxiliary ribbon, and means including two actuating fingers to swing about a common axis, one of said fingers engaging the line-space slide, and the other finger engaging the ribbon-controlling slide.

20. In a typewriting machine having a revolute platen, around which may be fed an outer statement-sheet and an inner ledger-sheet at the same time, and a collating table, the combination with a main vibrating ribbon for typing on said statement-sheet, and an auxiliary ribbon normally disposed along the printing line of said platen adjacent the rear side of said main ribbon, for typing on said ledger-sheet, of means for inserting and collating said statement and ledger sheets in said machine, to avoid smudging said statement-sheet during numerous insertions and withdrawals of the same, said means including a back-print-prevention shield for said auxiliary ribbon, and

mechanism for moving said auxiliary ribbon and said shield from typing position upwardly to an inserting and collating position adjacent the lower end of said collating table, to provide an increased space between said main ribbon and said shield for said statement-sheet, said auxiliary ribbon and said shield being disposed in their collating positions substantially parallel 10 with the work-face of said collating table.

21. In a typewriting machine having a revolute platen, the combination with a ribbon-vibrator for a main ribbon, of mechanism arranged for laterally feeding an auxiliary ribbon along the printing line of said platen, and a separate back-print-prevention shield for said auxiliary ribbon carried by said mechanism under tension, whereby said shield may support said auxiliary ribbon against sagging in the path of said main ribbon-vibrator.

22. In a typewriting machine including a revolute platen, an insertion chute for a statement sheet and a ledger-sheet at the rear of the platen, a table for holding the rear end of a proof-sheet clear of the insertion chute, a collating table at the delivery side of the platen for locating the statement and ledger sheets with relation to each other and to the proof-sheet, and means for holding the proof-sheet stationary during the insertion and collation of the statement and ledger sheets comprising a roll at the delivery side of the platen to press the proof sheet against the platen.

23. In a typewriting machine including a revolute platen, an insertion chute for a statement-sheet and a ledger-sheet at the rear of the platen, a table for holding the rear end of a proof-sheet clear of the insertion chute, a collating table at the delivery side of the platen for locating the statement and ledger sheets with relation to each other and to the proof sheet, means for holding the proof sheet stationary during the insertion and collation of the statement and ledger sheets, and means for holding the ledger sheet stationary while the statement sheet is adjusted thereover.

24. In a typewriting machine including a platen, a main ribbon, an auxiliary ribbon at the front and back of which work sheets are positioned, a swinging collating frame at the delivery side of the platen, and means operable by the collating frame when swung in one direction to withdraw the auxiliary ribbon a substantial distance from the platen.

25. In a typewriting machine including a platen, a main ribbon, a swingable frame carrying an auxiliary ribbon at the front and back of which work sheets are positioned, a swingable collating frame at the delivery side of the platen, and means operable by the collating frame when swinging in one direction to swing said ribbon-carry-

ing frame to withdraw said auxiliary ribbon a substantial distance from the platen.

26. In a typewriting machine including a platen, a main ribbon, an auxiliary ribbon at the front and back of which work sheets are positioned, a swingable collating frame at the delivery side of the platen, means operable by the collating frame when swinging in one direction to withdraw the auxiliary ribbon a substantial distance from the platen, and means for releasably holding the ribbon in its withdrawn position.

27. In a typewriting machine including a platen, a main ribbon, a swingable auxiliary ribbon-carrying frame, an auxiliary ribbon at the front and back of which work sheets are positioned, and cam and lever means for swinging said ribbon-carrying frame to withdraw said auxiliary ribbon from the platen.

28. A machine for typing and computing items to be billed and posted, having a revolute platen upon the front of which the types strike, a rear insertion guide chute for ledger and statement sheets, a support for holding the rear end of a proof-sheet in the machine clear of the guide chute, means for holding the proof sheet to prevent accidental displacement thereof while the statement and ledger sheets are being inserted and collated thereover, a main ribbon to make a permanent record on the statement sheet, an auxiliary ribbon between the statement and the ledger sheets to make a copy on the ledger sheet, and means for withdrawing the auxiliary ribbon a substantial distance from the platen.

29. A machine for typing and computing items to be billed and posted, having a revolute platen upon the front of which the types strike, a rear insertion guide-chute for ledger and statement sheets, a collating table at the delivery side of the platen to assist in collating the statement and ledger sheets with respect to each other and to the printing point, a ribbon to make a permanent record copy on the statement sheet, an auxiliary ribbon between the ledger sheet and the statement sheet, and means for withdrawing the auxiliary ribbon a substantial distance from the platen whereby the said sheets may be inserted without fouling the auxiliary ribbon.

30. In a typewriting machine, the combination of a revolute platen, a main ink-ribbon at the front of the platen, a sheet-collating table at the delivery side of the platen for a ledger-sheet and a bill-sheet to be collated in the machine and withdrawn once for each single-line item typed thereon, an auxiliary ribbon to intervene between the collated sheets, and means for shifting the auxiliary ribbon up from printing position to an idle sheet-collating position above the printing line and below the collating table.

and spaced a trifle from the platen, to permit insertion and adjustment on said table of a sheet between the auxiliary ribbon and the platen and of an outer sheet between the 5 ribbons, whereby said work-sheets may be relatively positioned or collated while the ribbon therebetween remains in displaced position.

31. In a typewriting machine, the combination of a revoluble platen, a main ink-ribbon at the front of the platen, a sheet-collating table at the delivery side of the platen for a ledger-sheet and a bill-sheet to be collated in the machine and withdrawn 10 once for each single-line item typed thereon, an auxiliary ribbon to intervene between the collated sheets, means for shifting the auxiliary ribbon up from printing position to an idle sheet-collating position above the 15 printing line and below the collating table and spaced a trifle from the platen, to permit insertion and adjustment on said table of a sheet between the auxiliary ribbon and the platen and of an outer sheet between the 20 ribbons, whereby said work-sheets may be relatively positioned or collated while the ribbon therebetween remains in displaced position, and releasable means for holding the sheets stationary where collated while 25 the auxiliary ribbon is returned to printing position.

32. In a typewriting machine, the combination of a revoluble platen, a main ink-ribbon at the front of the platen, a sheet-collating 30 table at the delivery side of the platen for a ledger-sheet and a bill-sheet to be collated in the machine and withdrawn once for each single-line item typed thereon, an auxiliary ribbon to intervene between the 35 collated sheets, means for shifting the auxiliary ribbon up from printing position to an idle sheet-collating position above the printing line and below the collating table and spaced a trifle from the platen, to permit 40 insertion and adjustment on said table of a sheet between the auxiliary ribbon and the platen and of an outer sheet between 45

the ribbons, whereby said work-sheets may be relatively positioned or collated while the ribbon therebetween remains in displaced 50 position, said collating table mounted at one portion only of the platen, and means for carrying around the platen a proof-sheet of substantially greater width than said table to project laterally of said table, said auxiliary ribbon when in its raised position permitting typing through said main ribbon directly upon the projecting side margin of 55 said proof-sheet.

33. In a typewriting machine, in combination, a main ribbon for writing on an outside statement-sheet, an auxiliary ribbon for writing upon an inside ledger-sheet, line-spacing mechanism for advancing the work including a proof-sheet behind said first-mentioned sheets, said line-spacing mechanism including a line-space lever, and an auxiliary ribbon-controlling mechanism including a lever actuatable to move the auxiliary ribbon from writing position to a work-inserting position to facilitate the insertion of fresh statement and ledger sheets at opposite sides of the ribbon, the auxiliary ribbon-shifting lever being located in proximity to the line-space lever so that it may be engaged and actuated at the same operation with the line-space lever or independently thereof. 75

34. A back-print-prevention device for a typewriting machine having a laterally-fed auxiliary ribbon, said device including a relatively non-inked absorbent strip stretched lengthwise of the platen at the printing line, said strip being positioned between individual plies of work-sheets to be fed relatively 80 to said strip, and resilient means to detachably hold said strip under tension in the direction of its length, so that said auxiliary ribbon will be braced thereby against sagging and the work-sheets may be readily advanced line by line relatively to said auxiliary ribbon. 90
